UNITED STATES PATENT OFFICE.

JOSEPH M. EDGAR, OF CHICAGO, ILLINOIS, ASSIGNOR TO THE SMITH & EGGE MANUFACTURING COMPANY, OF BRIDGEPORT, CONNECTICUT.

INDICATOR-LOCK.

SPECIFICATION forming part of Letters Patent No. 536,193, dated March 26, 1895.

Application filed November 30, 1894. Serial No. 530,457. (No model.)

To all whom it may concern:

Be it known that I, JOSEPH M. EDGAR, a citizen of the United States, residing at Chicago, in the county of Cook and State of Illinois, have invented certain new and useful Improvements in Indicator-Locks; and I do hereby declare the following to be a full, clear, and exact description of the invention, such as will enable others skilled in the art to which it appertains to make and use the same.

My invention relates to indicator locks, but has a special reference to locks which employ indicator mechanism like that shown and described in my pending application, Serial No. 15 519,953, filed August 10, 1894.

The object of my present invention is to provide an indicator lock in which it shall be impossible to open the lock without changing the combination indicated.

20 In the accompanying drawings, which form a part of this specification, Figure 1 is a side elevation of my improved lock; Fig. 2, a bottom view with the seal removed. Figs. 3, 4, 5, and 6, are plan interior views with the cover 25 and shackle removed, and showing respectively by degrees the positions assumed by the parts as they are operated from locked to unlocked conditions. Fig. 7 is a vertical sectional elevation of the lock showing the 30 several parts in locked condition; Fig. 8, a detail view of the key; Fig. 9, a view similar to Fig. 7 but showing the parts in unlocked condition; Fig. 10, a section at the line $\alpha-\alpha$ of Fig. 9; Fig. 11, a detail perspective of the 35 slide yoke; Fig. 12, a detail broken perspective of the bottom of the lock, showing particularly the portion thereof to which the key is adapted; Fig. 13, a bottom perspective of the lock showing a seal label part way inserted, and Figs. 14 and 15 are detail views of the ratchet and toothed wheels which are 40 carried by the rotary barrel.

Similar numbers and letters of reference denote like parts in the several figures of the 45 drawings.

1 is the casing of the lock, and 2 is a rotary sprocket drum journaled therein and provided on its periphery with sockets α extending across the face thereof which constitute 50 grasping points in the manner presently to be explained.

4, 5, 6, 7, are the indicator chains which are formed of equal sized links as shown, and are hinged together in each instance, said chains being carried around the drum 2, the hinges 5; forming protuberances b which snugly fit within the sockets α so that it will be clear that said drum and chains are in effect a sprocket wheel and sprocket chains. The chain 7 has one more link than the chain 6, 6, the chain 6 one more link than the chain 5, while the chain 5 has one more link than the chain 4, and each link has thereon any suitable number, letter or other character.

Secured within the casing is a graduated 65 support 3 around which the chains extend, so that it will be obvious that such chains are substantially endless belts carried by the drum 2 and support 3. The outer surfaces of these graduated parts of the support 3 against 70 which the chains lie are circular and smooth, so that when such chains are carried around they will drag with but very little frictional resistance around such surfaces.

The casing is provided with an opening c 75 usually protected by some transparent substance like glass or mica, through which the numbers or other characters on the chain links register in alignment.

The parts which I have heretofore described 80 are constructed and operated precisely as shown and described in my aforesaid pending application, and I make no claim herein to the indicating devices proper, my present invention being confined to the mechanisms for 85 controlling and effecting the locking and unlocking of the shackle.

The barrel is hollow at its lower end as seen at 8 and has a hub 9 provided with notches 10 projecting through the bottom plate 11 and 90 the lock casing and affording one of the journals of said barrel. 12 are guide slots formed in the casing 1 with which said notches register successively when the barrel is revolved.

The key which is shown at Fig. 8 consists 95 of a plain shank 13 from which project wards 14, 15. The upper ward 14 is longer than the ward 15 so that when the key is inserted within the barrel 2 the ward 14 will project beyond the hub 9 and above the inner face 100 of the casing 1. When the key is turned the barrel will be revolved and the ward 14 will

pass above said casing, so that it will be readily understood that the key cannot be withdrawn until the succeeding guide slot 12 registers with the notch which is engaged by said wards. The outer walls of the guide slots 12 act as stops against which the ward 14 abuts, so that the barrel can be turned by the key throughout a limited extent, which latter is predetermined by the movement of the barrel necessary to cause the belts to register the next succeeding combination. It will thus be clear that the key must be removed from the barrel and again inserted with the wards within a succeeding notch in the hub before a new combination can be indicated. This is an important feature since it prevents any overthrow of the barrel, and moreover makes it extremely difficult to successfully tamper with the indicating mechanism for the reason that the key cannot be employed as a means for rapidly revolving the barrel for the purpose of registering the entire number of combinations up to the combination upon which the lock was sealed.

25 The barrel, the graduated support and chains are all inclosed between the bottom plate 11 and a top plate 16, through which latter projects the upper hub 17 of the barrel. Between this top plate 16 and the upper wall of the casing of the lock is a space within which all the mechanism for effecting and controlling the locking and the unlocking is contained, which mechanism I will now describe.

30 Secured around the hub 17 is a toothed wheel 18 and a ratchet wheel 19, the latter being above the former.

35 20 is a yoke frame which rests upon the plate 16 and fits snugly between the side walls of the casing but is capable of a free sliding movement. This yoke is provided with a spur 21 which is within the field of travel of the ratchet wheel 19 so that when the latter is revolved one of the teeth thereof will engage said spur and cause the yoke to be carried rearward. The shackle 22 is pivoted at 23 at its heel end in the casing while its nose is provided with a notch 24, which latter is engaged by a bolt 25 carried by the yoke 20 whereby said shackle may be locked in closed position. When the yoke is withdrawn by the action of the ratchet as above explained, the bolt will be withdrawn from the notch 24 thereby unlocking the shackle.

40 55 26 is a dog pivoted at 27 to the plate 16 and having its nose 28 in engagement with the toothed wheel 18, so that as the latter is revolved the tail 29 of said dog will be swung outwardly.

60 65 30 is a pin carried by the yoke 20 and projected inwardly therefrom, and sustained around said pin is a coil spring 31 which bears against the head of the dog 26 to keep the nose 28 in normal engagement with the wheel 18.

When the parts are in normal position as

shown at Fig. 3, the tail 29 of the dog will be immediately in front of a projection 32 carried by the yoke, so that the latter cannot be moved to release the nose of the shackle until said tail is swung out of the way.

33 is a gate at the forward end of the yoke and contained between the projection 32 and a shoulder 34 which extends from the inner wall of said yoke, which gate is slightly wider than the tail 29 so that the latter will readily pass therein.

As the barrel is turned the tail 29 will move away from the projection 32 and will be swung immediately behind the shoulder 34 by the action of the toothed wheel 18 against the nose of the dog, as shown at Fig. 4, and while the parts are in this position it would be impossible to withdraw the bolt 25 from the shackle since the shoulder 34 would abut against the tail of the dog. By the time the parts have got to the position shown at Fig. 4, one of the ratchet teeth in the wheel 19 will have come into engagement with the spur 21, while at the same time the nose of the dog will be on top of one of the teeth in the wheel 18, and the continued turning of the barrel necessary to cause said tooth to pass beyond said nose will cause the yoke to be slightly withdrawn, so that when the tooth does pass the nose the projection 32 will have been retracted far enough so that the tail of the dog will be swung by virtue of the spring 31 against said projection and in position to enter the gate 33, as shown at Fig. 5. The tail of the dog is now free to enter the gate 33, and on the continued turning of the barrel the ratchet will act on the spur to withdraw the yoke completely and release the nose of the shackle from the bolt 25, as clearly shown at Fig. 6. It will be observed that the spring 31 will be under tension when the parts are in this position last referred to, and that the nose 28 of the dog will have been projected by the action of this spring between two of the teeth on the wheel 18. The dog when in this position acts as a detent to prevent the backward turning of the barrel, while the spring performs the double function of projecting said nose between the teeth of the wheel 18 and of normally advancing the yoke frame to locking position. It becomes necessary therefore to interpose some means whereby the yoke frame may be held in the position shown at Fig. 6 against the action of this spring.

35 is a plunger pin which extends vertically and loosely through suitable perforations in the plates 11, 16, and also through the bottom of the lock casing, said pin having affixed to the upper extremity thereof a head 36 which latter rests upon a coil spring 37 contained within a socket 38 depending from the plate 16, the function of which spring is to keep the head in a normally elevated position. When the nose of the shackle is in locking position

it will press down this head against the resiliency of the spring 37, as shown at Fig. 7, but when the shackle is released said head will immediately be projected upward in front of the bolt 25, as shown at Figs. 6 and 9, and will thereby prevent the return of the yoke frame to its normally advanced position. I prefer to make the shape and dimensions of this head in cross section the same as the corresponding shape and dimensions of the nose of the shackle, so that when the latter is unlocked said head will fill the opening in the top of the casing through which said nose in locked position projects, so that dirt or other foreign matter cannot get inside of the casing. I provide a shoulder 39 which extends laterally from the bottom of this head and abuts against the lock casing to limit the upward movement of said head so that the top of the latter will, when projected upwardly, be substantially flush with the outer face of the casing. When the shackle is closed the nose thereof will depress the head 36 as shown at Fig. 7.

25 At the bottom of the lock casing is formed a label case 40 within which any suitable seal label 41 may be inserted so as to entirely cover up the key hole. When the head 36 is depressed by the shackle the pin 35 will pierce this label, thus locking the same in position, as shown at Fig. 7, so that said label cannot possibly be removed without destroying it.

When it becomes necessary to open the lock the seal is simply cut through or otherwise broken so as to permit of the passage of the key, and after the shackle has been unlocked and the pin 35 raised, the mutilated label is then readily withdrawn from its case. It will thus be readily understood that the label must be first destroyed before the lock can be opened, and when it is borne in mind that the lock cannot be opened without changing the registration, it will be seen that it is well nigh impossible to tamper with the lock without leaving such clear evidence thereof as would enable an inspector to immediately perceive that such tampering had been effected.

It will be evident, from the foregoing description, that the dog 26 has two functions, namely, to prevent the retraction of the yoke by a sudden jar or tap against the lock casing, and to lock the barrel as against backward turning such as might be attempted to re-store a preceding combination. Separate springs may of course be employed for the dog and yoke, but I prefer to use a single spring which shall act both to throw the nose of the dog between the teeth of the wheel 18 and also to project the yoke into locking position.

My improved indicator lock is very readily assembled, for it will be seen that the indicator chains and the barrel and support for carrying the same are assembled and secured in position between the plates 11 and 16, and

therefore the locking mechanism may be removed for repairing or for other purposes without disturbing the indicating instrumentalities.

Having thus described my invention, what I claim as new, and desire to secure by Letters Patent, is—

1. In an indicator lock as described, the combination of the rotary barrel 2 provided with hub 17, the toothed wheel and ratchet wheel secured to said hub, the spring actuated dog having its nose in normal engagement with said toothed wheel, the yoke frame surrounding said wheels and dog and capable of a sliding movement within the lock casing and having a spur 21 within the field of movement of said ratchet and provided at its forward end with a gate and a shoulder and projection on opposite sides of said gate, the bolt 75 carried by the forward extremity of said yoke, the spring confined between said dog and yoke, the shackle pivoted within the lock casing and having a notched nose with which said bolt is capable of engaging, and the vertically movable resilient head 36, substantially as set forth.

2. The combination of the casing, the rotary barrel suitably journaled therein and provided with a hub, the toothed wheel 18 and ratchet wheel 19 secured to said hub, the pivoted dog 26 having its nose capable of engaging with the teeth in the wheel 18, the yoke frame 20 surrounding said wheels and dog and capable of a sliding movement and provided with spur 21, gate 33, projection 32, shoulder 34, and bolt 25, a spring for normally projecting the nose of said dog between the teeth of the wheel 18 and for normally advancing said frame to locking position, the shackle pivoted within the lock casing and having its nose provided with a notch 24 with which said bolt is adapted to engage, the pin 35 extending vertically through the lock casing and having a free movement therein and provided at its upper extremity with a head 36, and the spring 37 having a bearing against the under side of said head whereby the latter is normally projected upward, substantially as set forth.

3. The rotatory barrel 2 hollow at its lower end and provided with notched hub 9 which extends through the bottom of the casing, and the casing provided with guide slots at predetermined points with which said notches successively register, a key with two wards one longer than the other, the shorter ward being wholly contained within one of the notches in said hub while the longer ward extends beyond said hub and will when the latter is rotated be carried beneath said casing and thence into abutment against the outer wall of one of said guide slots, substantially as set forth.

4. The combination of the hub 17 having secured thereto the toothed and ratchet wheels, the resilient yoke frame surrounding said

wheels and having a sliding movement within said casing and provided with a spur which is within the field of movement of said ratchet wheel whereby when the latter is revolved 5 said frame will be forced backward against its resiliency, the pivoted resilient dog having its nose in normal engagement with the toothed wheel, the bolt carried by said frame, the shackle pivoted to the lock casing and 10 having a notched nose capable of being engaged by said bolt, and the vertically movable resilient head immediately below said shackle nose, substantially as set forth.

5. The combination of the hub having secured thereto the toothed wheel and ratchet wheel, the yoke frame within said casing and capable of a sliding movement and having at its forward end a gate and provided with a shoulder and a projection on opposite sides 15 of said gate, the pivoted dog, and the spring whereby said frame is normally advanced and the dog operated to bring its nose into en-

gagement with said toothed wheel and its tail immediately in the rear of said projection, substantially as set forth. 25

6. The combination of the pivoted shackle having its nose provided with a notch, the yoke frame capable of sliding freely and resiliently within the lock casing and carrying a bolt which engages with said notch and having at its rear end a spur and at its forward end a gate contained between a shoulder and projection, the hub having secured thereto the toothed wheel and ratchet wheel, and means for preventing the rotation of said toothed wheel excepting in one direction, substantially as set forth. 30 35

In testimony whereof I affix my signature in presence of two witnesses.
